UNITED STATES PATENT OFFICE.

JAMES S. HUGHES, OF ST. PAUL, MINNESOTA, ASSIGNOR TO DANA M. HUGHES, OF SAME PLACE.

TROLLEY-WIRE SUPPORT FOR ELECTRIC RAILWAYS.

SPECIFICATION forming part of Letters Patent No. 445,142, dated January 20, 1891.

Application filed April 19, 1890. Serial No. 348,686. (No model.)

To all whom it may concern:

Be it known that I, JAMES S. HUGHES, a citizen of the United States, residing at St. Paul, in the county of Ramsey and State of Minnesota, have invented certain new and useful Improvements in Trolley-Wire Supports for Electric Railways; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in supports for the trolley-wires of electric railways; and it consists, generally, in an arch of tubular form resting upon suitable posts at the sides of the street, the trolley-wires being suspended or otherwise supported from the arch.

The object of the invention is to do away with certain disadvantages attendant upon the use of the ordinary means of support, 25 consisting of poles located upon each side of the street, the poles being connected by means of cross-wires, from which the trolley-wires are supported. It is customary to set the poles at a considerable angle to the vertical, opposite poles inclining in opposite directions, and to draw them to a vertical position by means of the connecting cross-wires for the purpose of furnishing a degree of tension upon the cross-wires sufficient to prevent 30 sagging when the trolley-wires are attached. It becomes necessary in this construction to use poles of considerable size and strength in order to withstand the strain, and the tension of the cross-wire not only causes an unsightly curvature of the poles, but the variation 35 in the tension upon the wire, and in the capability of the poles to withstand the same, consequent upon changes in temperature, renders the construction dangerous. At the same time the size of the poles necessitated 40 solely by this tension adds greatly to the cost of construction.

The invention is illustrated in the accompanying drawings, in which—

50 Figure 1 represents a general view of my improved method of supporting trolley-wires,

and Figs. 2 and 3 are details of the joints between the several parts of the supporting-arch.

Upright posts 1 1 are erected at each side 55 of the street, and between opposite posts, its extremity resting thereupon, is sprung an arch 2, spanning the street. The arch is of tubular construction, of semi-elliptical or semi-circular form, or of any other curvature 60 suited to the width of the street and the necessary height of the trolley-wires above the ground. For the purpose of securing as great strength as possible with little weight, the arch is preferably constructed in three or 65 more sections, the extremities 3 3 for some distance from the top of the posts being of larger diameter than the middle portion 4. For instance, the posts may be three inches in diameter, the extremities of the arches two 70 inches, and the middle part about one and one-half or one and three-quarters inch. This proportion may, however, be varied at will, according to the width of the street and the curvature of the arch. From the middle 75 section of the arch the trolley-wires 5 5 are supported, either by hangers 6 6, insulated from the arch or the wire, or both, or in any other convenient manner. It will be observed that the weight upon the arch is borne 80 by the posts 1 1 vertically, and that there is no side strain whatever, thus enabling posts of small section to be used. For the same reason the arch may be constructed of a weight sufficient only to simply sustain the weight 85 of the trolley-wires, and the arch form is well known to sustain the greatest load in proportion to the weight of material. The leader-wire 7 and feeders 8 may be supported by the arch and connect with the trolley-wires in the 90 usual manner.

As a further improvement and as a measure of safety on account of possible defective insulation between the wires and the arch, the tubular sections forming the extremities 95 of the arch are insulated from the posts by means of a form of joint shown in Fig. 2. The posts 1 are preferably of tubular form, and have an inner diameter sufficient to admit the end of the end sections 3 and leave 100 considerable space between the two. This space is filled with some non-conducting sub-

stance 10, preferably sulphur, on account of its small conductivity, and also for the reason that it is peculiarly efficient in setting the joint. The end section of the arch is centered with respect to the post by means of a cap 11, of non-conducting material, as earthenware, closely fitting the circumference of the section 3, and having a flange 12, adapted to overlap the top of the post, and by means of a plug 13 of non-conducting material inserted and retained within the post at some distance from its top, and having a central boss 14, adapted to enter the end of the section 3 when abutted against the plug. The cap 11 may then be moved away from the joint and the melted mineral poured in, setting the joint, while the cap on being restored to its place serves as a protection to the action of the weather upon the insulating material.

The connection between the middle and end sections of the arch may be formed by screw-threads, as shown in Fig. 3, or by means of a sleeve-nut, or in any other suitable manner, either insulated or otherwise.

The posts 11 may be made, if found desirable, of material of small conductivity, as wood, papier-maché, &c., thereby avoiding the necessity of insulation between the same and the arch.

By means of the construction herein set forth it is believed that not only is a superior form of support obtained, but that grounding of the current by way of the support is absolutely impossible, insuring a greater degree of safety to the public than by means of the supports hitherto employed.

I claim as my invention—

1. A support for the trolley-wires of electric railways, consisting of a tubular arch

spanning the roadway, the wires being supported from the middle portion thereof by insulated connections and the extremities of said arch insulated from the ground, as and for the purpose specified.

2. A support for the trolley-wires of electric railways, consisting of a tubular arch, from the middle part of which the said wires are adapted to be supported, the said arch being formed in sections of gradually-increasing diameter from the middle to the ends thereof, as and for the purpose specified. 45

3. A support for the trolley-wires of electric railways, consisting of a tubular arch, from the middle part of which the said wires are adapted to be supported, the said arch being supported upon upright posts at each side of the roadway, and a non-conducting material forming the connection between the extremities of the curved portion of the arch 55 and said upright posts, as and for the purpose specified.

4. A support for the trolley-wires of electric railways, consisting of a tubular arch, from the middle portion of which the said wires are adapted to be suspended, the said arch being constructed in sections of increasing diameter from the middle to the extremities thereof, upright posts upon which the ends of the arch are supported, and a non-conducting cap forming connection between the extremities of said arch and said posts, substantially as and for the purpose herein specified. 65

In testimony whereof I affix my signature in presence of two witnesses.

JAMES S. HUGHES.
